UNITED STATES PATENT OFFICE

163,348

SHIRT

Braden Ball, Pensacola, Fla.

Application June 25, 1948, Serial No. 147,205

Term of patent 7 years

(Cl. D3—25)

To all whom it may concern:

Be it known that I, Braden Ball, citizen of the United States, residing at Pensacola, in the county of Escambia and State of Florida, have invented a new, original, and ornamental Design for a Shirt, of which the following is a specification, reference being had to the accompanying drawing, forming part thereof.

In the drawings:

What I claim as my invention is:

The ornamental design for a shirt, substantially as shown.

BRADEN BALL.
